UNITED STATES PATENT OFFICE

2,454,203

SPINNING APPARATUS

Paul R. Powell, Baltimore, Md., assignor to Western Electric Company, Incorporated, New York, N. Y., a corporation of New York

Application February 28, 1946, Serial No. 650,999

9 Claims. (Cl. 113—24)

1

This invention relates to spinning apparatus and more particularly to apparatus for sealing covers on cylindrical articles.

An object of the invention is to provide new and improved spinning apparatus.

Another object of the invention is to provide means for sealing covers on cylindrical articles wherein the article is maintained in a non-rotative position during the sealing operation.

A further object of the invention is to provide a spinning machine for sealing dust covers on potentiometer housings which requires a minimum of supervision and manual control.

In accordance with a specific embodiment of the invention there is provided a spring loaded means for supporting a cup-shaped cover in which a potentiometer may be positioned, a constantly rotating flyer carrying a plurality of spinning members adjacent to the cover supporting means, and means for urging the cover supporting means downwardly whereupon the spinning members are thrust inwardly and engage the periphery of the cover so as to turn over an annular flange against a shoulder of the potentiometer housing positioned therein.

A clear understanding of the invention will be had from the following detailed description of a specific embodiment thereof, when read in conjunction with the appended drawings, in which:

Fig. 1 is a side elevation of an apparatus forming a specific embodiment of the invention in which portions of the apparatus are broken away for reasons of clarity;

Fig. 2 is a horizontal, sectional view of a portion of the apparatus taken along line 2—2 of Fig. 1;

Fig. 3 is a fragmentary, vertical, sectional view of a portion of the apparatus taken along line 3—3 of Fig. 2;

Fig. 4 is a fragmentary, vertical, sectional view of the apparatus taken along line 4—4 of Fig. 2;

Fig. 5 is substantially the same as Fig. 4 except that the movable parts of the apparatus are shown in their final operating position, and

Fig. 6 is an enlarged, fragmentary, sectional view of a portion of the apparatus.

Referring now to the drawings and more particularly to Figs. 1 and 4, a motor 9 serves to drive a flyer 10 by means of a V-belt 11. The flyer 10 is rotably mounted on a tubular portion 12 of a spring loaded support 13 by means of an anti-friction bearing 14. An outer ring 15 of the bearing 14 is positioned within an annular groove 16 cut in the flyer 10 and is rigidly secured therein by means of a retainer ring 17 fastened to the flyer 10 by a plurality of bolts 18—18. An

2

inner ring 19 of the anti-friction bearing 14 is rigidly fitted over the periphery of the tubular portion 12 of the support 13 and maintained in engagement with a shoulder 20 provided in the upper portion 12 by means of a clamping ring 21 rigidly secured to the upper portion 12 by a plurality of bolts 22—22. The ring 21 is provided with a shoulder 23 which abuts against the inner ring of the anti-friction bearing 14 so as to leave a clearance space between the shoulder 23 and the top of the upper portion 12 of the support 13, whereby the ring 21 serves to rigidly clamp the bearing 14 to the support 13. A leather sealing ring 24 is positioned on the periphery of the upper portion 12 adjacent to the bearing 14 and within the retainer ring 16 for the purpose of preventing the bearing lubricant from being thrown therefrom during the rotation thereof.

The support 13 has an elongated, cylindrical body portion 26 slidably positioned within a tubular support 27, which is rigidly secured to a plate 30 centered in a ring 31. The ring 31 is rigidly secured to a base plate 33 by means of a plurality of posts 32—32. The base plate 33 is secured to a top 34 of a suitable work bench, a portion of the frame of which is designated 35. The tubular support 27 is lined with a plurality of bushings 36—36, which provide a sliding fit for the body portion 26 of the support 13. The support 13 is also provided with a plurality of rods 37—37 rigidly secured adjacent to the periphery of a shoulder 40 and extend downwardly therefrom through a plurality of bores 41—41 provided in the plate 30. The rods 37—37 have their lower portions 42—42 substantially reduced in diameter thereby forming shoulders 43—43 against which are placed washers 44—44.

Springs 45—45 are positioned over the lower portions 42—42 of the rods 37—37 between the washers 44—44 and a ring 46, which is maintained in its respective position by means of a nut 47 mounted on a threaded portion 50 of the tubular support 27. The springs 45—45 serve to resiliently support the support 13 and the flyer 10 rotatably mounted thereon. The support 13 has a circular plate 51 secured on the face of the body portion 26 by means of a plurality of bolts 52—52. By adjustment of the nut 47, the springs 45—45 are compressed and serve to urge the support 13 upwardly, whereby the plate 51 abuts the end surface 53 of the tubular support 27. The upper portion 12 of the support 13 is provided with a bore 55, in which is positioned a flanged portion 56 of the ring 21. The ring 21 is provided with a bore 60, in which is slidably positioned a tubular

body portion 61 of a funnel-shaped support 62 having a hollow, conical end 63.

A pedestal-shaped support 64 has a circular top 65 slidably positioned within a wall 66 of the conical end 63. The support 64 is provided with a tubular body portion 67, which protrudes into the body portion 61 of the support 62. The support 64 is resiliently mounted in the support 62 by means of a heavy compression spring 68, which surrounds the tubular body portion 67 and abuts the underside of the top 65 and a plurality of shims 69-69 positioned on a shoulder 70 provided on the inside of the tubular body portion 61. The relative positions of the support 62 and the support 64 are maintained against the action of the compression spring 68 by means of a nut 71 threadedly positioned on the tubular portion 67 of the support 64, whereby the top 65 thereof is drawn into the bore 66 of the support 62. The support 64 is resiliently mounted on the support 13 by means of a heavy compression spring 72, which is positioned within the tubular body portion 67 of the support 64.

The support 64 has a rod 73 rigidly secured in a central bore 74 provided in the top 65 and extends therefrom through an elongated bore 75 in the body portion 26 of the support 13. The rod 73 is threaded on its opposite end to receive a plurality of nuts 76-76, whereby the support 62 and the support 64 may be drawn as a unit into the tubular body portion 12 of the support 13 against the action of the compression spring 72. The space between an end 77 of the tubular body portion 67 and a bottom 78 of the bore 55 can thereby be adjusted to obtain the required vertical travel between the support 64 and the support 13. This adjustment of the supports 62 and 64 as a unit within the tubular body portion 12 by means of the rod 73 and the nuts 76-76 does not affect the relative position of the support 64 with respect to the support 62 previously set by means of the spring 68 and the nut 71 because the spring 68 only has to overcome the sliding fit of the support 62 within the bore 55 of the tubular body portion 12. The top 65 of the support 64 is provided with a cup-shaped recess 80 for receiving a formed metal cover, such as a cover 81, which is to be sealed on a potentiometer housing, such as a housing 82.

A ram 85 (Fig. 1) is positioned above and centrally aligned with the potentiometer housing 82 and the supporting members 13, 62 and 64. The ram 85 is reciprocated by means of a double acting air cylinder 86 rigidly secured to a channel-shaped supporting member 87 mounted on the base plate 33. The air cylinder 86 has a piston (not shown) positioned therein which is directly connected to the ram 85 by means of a rod 90. Movement of the piston and the ram 85 is controlled by a conventional, three-way air valve 91 secured to the support 87. The valve 91 is provided with a lever 92, which serves to connect the air cylinder 86 to a source of compressed air (not shown) through its associated pipe lines 93-93. When the lever 92 is in the position shown in Fig. 1, the valve 91 serves to admit compressed air to the bottom of the cylinder 86 and thereby maintain the ram 85 in its raised position. When the lever 92 is turned to the right, the valve 91 serves to admit air to the top of the air cylinder 86 and thereby force the ram 85 downwardly into engagement with the potentiometer housing 82 and thereafter urge the housing and the supporting members 13, 62 and 64 into their respective positions shown in Fig. 5.

A plurality of spinning members 100-100 (Fig. 2) are carried by the flyer 10 by means of a plurality of pins 101-101 rigidly positioned in bores 102-102 provided in the flyer 10 (Figs. 3 and 4). Bushings 103-103, having eccentric bores 104-104 therethrough, are adjustably positioned on the pins 101-101 by means of set screws 105-105. Both ends of each of the bushings 103-103 are provided with under cut portions 106-106 on which are rotatably positioned an upper arm 110 and a lower arm 111 of the spinning members 100-100. The upper arm 110 and the lower arm 111 of the spinning members 100-100 are rigidly maintained in parallel relationship by means of a bolt 112 which clamps the arms 110 and 111 against an oblique cylindrical bushing 113 (Fig. 3) by means of a nut 114 threaded on the lower end of the bolt 112. An anti-friction roller 115 is rotatably positioned on the bushing 113 and maintained thereon by means of a conventional lock nut 116 mounted on a threaded portion 120 of the bushing 113.

Each of the spinning members 100-100 is provided with a forming roller 121, rotatably positioned on a pin 122, which is positioned in a bore 123 in the arm 110 and a bore 124 in the arm 111. Each pin 122 is provided with a pair of shoulders 125-125 which serve to space the arms 110 and 111 the proper distance apart at this point. Each pin 122 has positioned thereon a flanged bushing 126, which is engaged by a spring 127 positioned over the pin 122 and serving to maintain the forming roller 121 close to the arm 110. Each pin 122 is secured to the spinning members 100-100 by means of a nut 128 threadedly secured on the lower ends of the pin 122. Each of the arms 110-111 extends a substantial distance beyond the roller 121 so as to slidably engage one of a plurality of lugs 130-130 secured to the flyer 10. Each of the lugs 130-130 has an overhanging portion 131, which, together with a shoulder 132 on the bushing 103, serves to maintain its adjacent spinning member 100 against spacers 133-133 secured to the flyer 10. The anti-friction rollers 115-115 positioned on the bushings 113-113 are inclined with respect to the pins 112-112, so that they make a line contact with a tapered bore 135 of an annular cam 136 (Figs. 4 and 5). The annular cam 136 is positioned within a bore 140 in the base plate 33 and is maintained therein by means of a shoulder 141 provided on the upper portion of the annular cam 136.

A cup-shaped stop nut 150 (Fig. 4) is threadedly mounted on the threaded portion 50 of the tubular support 27 and maintained in any selected position thereon by means of a set screw 151. The set screw 151 is threadedly mounted in the wall of the nut 150 and serve to force a soft metal insert 152 against the threaded portion 50 of the support 27. The stop nut 150 is positioned on the tubular support 27 so that there is a predetermined space between the plate 51 and the inner surface 154 of the stop nut 150. A circular guard 155 has an annular flanged portion 156 rigidly secured to the base plate 33 and serves to protectively cover and constantly rotating spinning members 100-100.

Each of the forming rollers 121-121 has an irregularly shaped periphery, which comprises a shoulder 160 (Figs. 4 and 6) formed adjacent to its upper face and an annular beveled portion 161 formed adjacent to its lower face. The shoulder 160 and the beveled portion 161 are joined by an undercut portion 162. The shoulder 160

serves to engage an upper portion of a flange 163 of the cover 81 and thereby roll over a portion thereof to form an annular edge 164 (Fig. 6) against a shoulder 165 provided on the potentiometer housing 82 (Figs. 5 and 6). The annular beveled portion 161 coacts with the beveled surface 166 of the support 62 whereby the forming rollers 121-121 of the spinning members 100-100 are urged downwardly against the action of the spring 127, thereby causing the shoulder 160 to roll the edge 164 tightly against the shoulder 165 of the potentiometer housing 82.

The above-described apparatus operates in the following manner:

The loading position of the respective elements of the spinning machine is shown in Figs. 1 and 4. Assuming that the motor 9 has been energized, the flyer 10 is thereby rotated about the stationary support 13. The flyer 10 causes the plurality of spinning members 100-100 mounted thereon to be revolved about the supports 62 and 64, whereby the anti-friction rollers 115-115 thereon roll around the upper portion of the tapered bore 135 of the annular cam 136. Centrifugal force acting on the revolving spinning members serves to maintain the rollers 115-115 in engagement with the bore 135 of the annular cam 136, whereby the forming rollers 121-121 are merely revolved about the support 64 without being forced inwardly by the annular cam. The spinning members 100-100 can be adjusted by means of the eccentric bushings 103-103 so that each of the forming rollers 121-121 will be positioned equidistant from the center of the support 64.

A potentiometer cover, such as a cover 81, is placed in the cup-shaped recess 80 of the support 64, whereupon a flanged portion 167 thereof rests upon a face 168 of the said support. A cork gasket 170 is positioned on the inside surface of the said flanged portion 167 of the cover 81 and a potentiometer housing 82 is placed on the cork gasket 170 (Figs. 4 and 6). The lever 92 of the air valve 91 is actuated to the right, whereupon the ram 85 is forced downwardly and engages the potentiometer housing 82. As its downward stroke continues, the ram forces the support 64 and the support 62 downwardly as a unit against the action of the compression spring 72 until the surface 77 of the support 64 abuts the surface 78 of the support 13. During this portion of the stroke of the ram 85, the support 13 is maintained in a stationary position because the plurality of compression springs 45-45 exert a greater force against movement than does the single compression spring 72.

When the end 77 of the body portion 67 abuts the surface 78 of the support 13, the potentiometer cover 81, the support 64 and the support 62 are now adjacent to the forming rollers 121-121 of the revolving spinning members 100-100. As the ram 85 continues on its downward stroke, the support 64 and the support 13 now move downwardly as a unit against the action of the springs 45-45. As the support 13 is urged downwardly, it carries therewith the flyer 10 and the revolving spinning members 100-100, whereupon the anti-friction rollers 115-115 of the spinning members 100-100 move downwardly in the tapered bore 135 of the annular cam 136. The spinning members 100-100 are maintained in the tapered bore 135 during the downward movement therein by means of the overhanging portion 131 of the lug 130 and the shoulder 132 provided on

the bushing 103. Due to the fact that the rollers 115-115 are now travelling around a smaller diameter of the tapered bore 135, the spinning members 100-100 are rotated inwardly about the bushings 103-103, whereby their respective forming rollers 121-121 are forced into engagement with the flange 163 of the potentiometer cover 81. The forming rollers 121-121 now roll around the periphery of the flange 163, and the shoulder 160 thereof serves to turn over the annular edge 164 of the cover against the shoulder 165 on the potentiometer housing 82. At the same time the annular bevel 161 provided on the forming rollers 121-121 engages the annular bevel 166 of the support 62 and the forming roller is thereby urged downwardly, whereby the shoulder 160 is pressed hard against the turned-over edge 164 (Figs. 5 and 6). The downward movement of the forming rollers 121-121 caused by the co-action of the beveled surfaces 161 and 166 is permitted by the compression spring 127 positioned between the forming rollers 121-121 and the lower arm 111 of the spinning members 100-100. However, due to dimensional variations existing in the cover 81, the cork gasket 170 and the shoulder 165, the forming rollers 121-121 may completely turn over the annular flange 164 before the support 13 completes its full travel. When this condition occurs, the coaction of the beveled surfaces 161 and 166, due to the inward travel of the spinning members 100-100, causes the support 62 to be lifted up against the action of the spring 68, thereby preventing the forming rollers from scoring the annular flange 164 of the cover 81.

When the ram 85 has caused the plate 51 to engage the surface 154 of the stop nut 150, further downward travel of the ram 85 is prevented, and the spinning operation which seals the cover 81 on the potentiometer housing 82 is completed. The lever 92 of the air valve 91 is now returned to its vertical position (Fig. 1), whereupon the ram 93 returns to its normal starting position. The springs 45-45 and the spring 72 serve to return the flyer 10, the support 13, the support 62, the support 64 and the potentiometer housing 82 to their respective loading positions. The finished potentiometer then may be removed from the support 64 and another cover, gasket and potentiometer may be placed thereon and the cover secured in place by the spinning operation described above.

While directed particularly to sealing metal covers on potentiometer housings, the invention is generally applicable to a wide range of spinning operations, products and apparatus, and therefore is to be limited only by the scope of the appended claims.

What is claimed is:

1. Spinning apparatus, comprising means for resiliently supporting a circular cover which is to be sealed on a cylindrical article, a flyer rotatably mounted on the support and movable therewith, means for constantly revolving said flyer, a plurality of arms pivotally mounted on said flyer, forming rollers rotatably mounted on the extremities of said arms, guide rollers angularly positioned intermediate the ends of the arms, an annular cam positioned adjacent to said flyer and having a converging bore in engagement with said angularly positioned rollers, means for aligning the periphery of the cover with said forming rollers, and means for causing said angularly positioned rollers to roll around

a portion of said converging bore having a smaller diameter, whereby said forming rollers are urged inwardly into engagement with the periphery of said cover to thereby turn over an annular edge of said cover against a cylindrical article.

2. An apparatus for spinning covers on cylindrical articles, comprising a fluid operated press including a ram, a spring loaded support having a recess therein for receiving a formed cover and an article to which it is to be secured, said supporting means being aligned with the ram of said press, a flyer rotatably mounted on said supporting means and movable therewith, an annular cam positioned adjacent to said flyer, a plurality of arms pivotally mounted on said flyer, spinning rollers rotatably mounted on said arms, guide rollers angularly positioned on the arms so as to rotatably engage the annular cam, and means for causing the press to urge the cover receiving means downwardly, whereby the arms are forced inwardly by the coaction of the guide rollers and the annular cam so that the spinning rollers turn over an annular flange on the cover.

3. Spinning apparatus, comprising a fluid operated press including a reciprocable ram, a spring loaded member in alignment with said ram and having a recess therein for receiving a cup-shaped cover, a rotatably mounted flyer surrounding the spring loaded member and movable therewith, means for rotating the flyer, a stationary annular cam positioned coaxially with respect to the flyer, a plurality of arms pivotally mounted upon the flyer, rollers rotatably mounted upon the arms intermediate the ends thereof so as to engage the annular cam, and forming rollers mounted on the ends of the arms, whereby when the ram of the press is advanced into engagement with a cover positioned in the cover-receiving recess, the forming members are forced inwardly by the coaction of the rollers and the annular cam to cause the forming rollers to form an edge of the cover into a desired configuration.

4. An apparatus for spinning covers on cylindrical articles, comprising a spring loaded support having a recess therein for receiving a cup-shaped, circular cover and an associated cylindrical article to which the cover is to be sealed, a plurality of pivotally mounted arms, spinning rollers mounted on the extremities of said arms, guide rollers centrally positioned on said arms and inclined with respect thereto, an annular cam positioned adjacent to said arms and having a tapered bore therethrough, means for constantly revolving said arms to cause said guide rollers to engage the tapered bore of said cam, and means for urging the spring loaded support downwardly so as to bring the cover positioned therein adjacent to the spinning rollers and to urge the guide rollers downwardly in the tapered bore, whereby said spinning rollers are forced inwardly into engagement with the periphery of the cover so as to turn over its edge and seal the cover to the associated article.

5. Spinning apparatus, comprising means for resiliently supporting a formed cover during a spinning operation, said supporting means including a funnel-shaped support and a pedestal-shaped support resiliently positioned therein, said funnel-shaped support having an annular bevel adjacent to its periphery, a plurality of resiliently mounted spinning rollers, said spinning rollers having an irregularly shaped periphery comprising a forming shoulder adjacent to

one face, an annular bevel adjacent to its opposite face and an undercut portion therebetween, means for constantly revolving said spinning rollers about said supporting means, means for disposing the supporting means and a cover positioned therein adjacent to said spinning rollers, and means for urging the spinning rollers inwardly so that the shoulder thereon engages the periphery of said cover, and the annular bevel thereon simultaneously engages the annular bevel of said supporting means, whereby the shoulder serves to turn over an annular flange on said cover and the coaction of the said beveled surfaces serves to urge the forming shoulder downwardly against said turned-over flange and to lift said funnel-shaped support when said annular flange is completely formed by said shoulder.

6. An apparatus for sealing covers on cylindrical articles, comprising a pedestal-shaped support having a recess provided therein for receiving a circular cover having an upright flanged portion in which a cylindrical article is positioned, a spring loaded support having a tubular body portion in which the pedestal-shaped support is resiliently carried, a base plate, a tubular support rigidly secured to the base plate and having a portion of the spring loaded support slidably positioned therein, a rotatable flyer, means for constantly rotating said flyer about the spring loaded support, a plurality of upright posts rigidly secured to said flyer, an arm pivotally mounted on each of said posts, an annular cam rigidly secured to said base plate and having a tapered bore therethrough, guide rollers angularly mounted on said arms and engaging a portion of said tapered bore, spinning rollers rotatably mounted on the extremities of said arms, and means for urging the pedestal-shaped support, the cover and an article positioned therein downwardly, whereby the tapered bore of said cam urges the pivotally mounted arms inwardly causing the spinning rollers carried thereby to engage the upright flanged portion of said cover and to turn over a portion of said flanged portion against a shoulder on the cylindrical article.

7. An apparatus for sealing circular covers on cylindrical articles, which comprises a pedestal-shaped support having a recess therein for receiving a cover and an associated cylindrical article on which the cover is to be secured, a spring loaded support having a tubular body portion in which the pedestal-shaped support is resiliently positioned, means for permitting a predetermined travel between the pedestal-shaped support and the spring loaded support, means for providing a predetermined travel for the spring loaded support, a flyer rotatable about the spring loaded support, means for constantly rotating the flyer about said support, a plurality of pivotally mounted spinning members carried by said flyer, each of spinning members including a guide roller positioned at the center thereof and a forming roller rotatably mounted at the end thereof, an annular cam having a converging bore in which said guide rollers constantly roll, means for urging the pedestal-shaped support downwardly, whereupon the cover is positioned adjacent to the forming rollers of the revolving spinning members, and means for causing the pedestal-shaped support and the spring loaded support to move as a unit, whereby the guide rollers are forced downwardly and engage a smaller diameter of the converging bore, thereby causing the forming rollers to engage the periphery of the cover and turn

over an annular flange thereof so as to seal it to the cylindrical article.

8. Spinning apparatus, comprising means for resiliently supporting a circular cover which is to be sealed on a cylindrical article, a plurality of pivotally mounted spinning members positioned coaxially with respect to and substantially below the supporting means, means for revolving the spinning members around the central axis of the supporting means, a forming roller rotatably and resiliently mounted on each of the spinning members, means for urging the supporting means downwardly against the resilient supporting means to position the periphery of said cover adjacent to said forming rollers, camming means for urging the spinning members inwardly after the supporting means is urged downwardly thereby causing the rollers to roll around the periphery of the cover and turn over an annular edge thereon, and means provided on the resiliently mounted supporting means for urging the forming rollers downwardly with respect to the arms against the turned-over annular edge of the cover so as to tightly seal the cover on the cylindrical article.

9. An apparatus for sealing covers on cylindrical articles, which comprises a resiliently mounted support having a recess therein for receiving a cover and an associated cylindrical article on which the cover is to be secured, a plurality of pivotally mounted arms, means for constantly revolving said arms about the central axis of the support, a stationary annular cam positioned coaxially adjacent with respect to the revolving

arms and having a tapered bore therethrough, a forming roller positioned on each of the arms, a guide roller positioned on each of said arms so as to engage the tapered bore of said annular cam, and means for successively urging the support downwardly to first position said support and the periphery of the cover positioned therein adjacent to said forming rollers and then cause the rollers on the pivotally mounted arms to engage a smaller diameter of the tapered bore of the cam, thereby causing the forming rollers to move inwardly against the periphery of the circular cover and roll over the edge of the cover.

PAUL R. POWELL.
